John H. Parmenter Inventor.

United States Patent Office.

JOHN H. PARMELEE, OF CHICOPEE, MASSACHUSETTS, ASSIGNOR TO HIMSELF AND WILLIAM BALL.

Letters Patent No. 67,134, dated July 23, 1867.

IMPROVEMENT IN COLLARS.

The Schedule referred to in these Letters Patent and making part of the same.

TO ALL WHOM IT MAY CONCERN:

Be it known that I, JOHN H. PARMELEE, of Chicopee, in the county of Hampden, and Commonwealth of Massachusetts, have invented a new and useful Improvement in Collars, which I denominate a Neck-Tie Supporter; and I do hereby declare that the following is a full, clear, and exact description thereof, reference being had to the accompanying drawings, making a part of this specification, and to the letters of reference marked thereon, in which—

Figure 1 is a plan view of a paper collar with my invention applied.

In putting on a collar, where a neck-tie is used, the tie is first placed under the fold, and the collar is then buttoned on, and during this operation the tie often drops out from under the fold, and causes great annoyance and inconvenience. The tie and collar when removed from the neck often become separated, but by using this device this difficulty is also entirely removed, as the tie and collar need never be separated unless it is desired.

The nature of my invention consists in forming one or more tongues, either of a semicircular or semi-elliptical or rectangular shape, in the band of a paper or cloth collar for the purpose of keeping the tie from dropping out from under the fold while the collar is being adjusted to the neck, or while being worn, and entirely obviating the difficulties above mentioned.

To enable others skilled in the art to make and use my invention, I will proceed to describe its construction and application to use.

At *a*, in the band of the collar, that portion of the material between the curved lines is cut out, leaving a space into which the tie can be slipped. This support or tongue may be of any desired form, or shape, but I prefer that it should be of a semicircular or semi-elliptical form, so that there shall be as few corners as possible to catch against the tie as it may be drawn through either way, as it is often desirable to do. The tongue may be made, however, by simply cutting through the band in a semicircular or semi-elliptical form, as is represented at *b*, or it may be made as shown at *d*, with the curved line *d* cut in the band, and terminating at each end in the circular perforations or holes *c c*, as these perforations *c c* render the tongue *e* stronger, and less liable to be torn down from any downward strain of the tie, which might occur. I regard these different shapes, however, as modifications of the same thing, and do not confine myself to any one of them; but I do wish to confine myself to a semicircular, semi-elliptical, or rectangular form when the top is cut and forming a distinct loop or tongue, as I disclaim any and all methods of making such a tie-supporter by cutting simple straight lines or slits through the band, where one end of the tie has to be passed through one and out of another cut or slit in order to secure it, as I am aware that method has been used before. To that method, however, there is great objection, as it is often difficult to pass the tie through such slits or cuts, occupies more time in adjustment, and if it is desired to draw the tie either one way or another it is more difficult to do so, as the paper, on both sides of the slit, binds or presses against the tie and prevents it from passing through the slit; whereas my device—the tongue being free at the top—does not bind against the outer surface of the tie, but only against the bottom edge of the tie to prevent it from dropping down, and so the tie can be more easily drawn either way in its adjustment to the neck.

In its application to use it is only necessary to raise the outside of the collar, if a Byron or turn-down collar, insert the tie behind the loop or tongue, and then adjust the collar to the neck; and this device may be applied to a stand-up collar also, for the purpose of supporting the tie or scarf and keeping it in place while being worn.

Having thus described my invention, what I claim as new, and desire to secure by Letters Patent, is—

As a new article of manufacture, a paper or cloth collar having one or more semicircular, semi-elliptical, or rectangular slits or cuts in the band thereof, forming a tongue, made substantially as herein described and for the purposes specified.

JOHN H. PARMELEE.
